CLAIM

The ornamental design for a liquid-dispensing compartmented lid, as shown and described.

DESCRIPTION

FIG. 1 is a view of a liquid-dispensing compartmented lid showing my new design from above.

FIG. 2 is a view of the liquid-dispensing compartmented lid from one side.

FIG. 3 is a view of the liquid-dispensing compartmented lid from below.

FIG. 4 is a three-quarters perspective view of the liquid-dispensing compartmented lid.

FIG. 5 is the same three-quarters perspective view of FIG. 4 cut-away to show the design of the lid within; and,

FIG. 6 is the same three-quarters perspective view of FIG. 4 showing the liquid-dispensing compartmented lid having an optional closure or seal.
